UNITED STATES PATENT OFFICE.

DAVID R. KNAPP, OF PHILADELPHIA, PENNSYLVANIA, ASSIGNOR TO CO-OPERATIVE UTILITIES CO., INC., OF PHILADELPHIA, PENNSYLVANIA, A CORPORATION OF DELAWARE.

SELF LOADING AND UNLOADING SCRAPER AND METHOD FOR OPERATING THE SAME.

Application filed March 24, 1922. Serial No. 546,374.

To all whom it may concern:

Be it known that I, DAVID R. KNAPP, a citizen of the United States, residing at Philadelphia, in the county of Philadelphia and State of Pennsylvania, have invented certain new and useful Improvements in Self Loading and Unloading Scrapers and Methods for Operating the Same, of which the following is a specification.

10 This invention relates to that class of mechanical devices employed in mines for transferring loose material blasted from the working faces in the chambers to the cars in the entries, and more particularly to those scrapers that are especially adapted to be drawn by ropes into and out of thin flat cuttings in coal mines, but which, of course are workable in seams of practically any height, and for removing other material or metals 20 than coal from the mine to the car or from one place to another.

The present method of removing the loose coal is to provide means to place a car adjacent to the face and load the same by

25 manual means. In thin veins this is very expensive, as a considerable amount of bottom or top will have to be removed to provide head-room for the operation of the cars and also it is difficult for men to work in 30 these restricted places, the result being that this coal is not mined, due to expensive costs, and considerable production is thereby lost.

It is therefore the principal object of my 35 said invention to first, provide a mechanical device in the form of a scraper that is self-loading and unloading; second to provide a scraper construction that will handle large lumps of material; third, to provide a method of scraper operation that requires 40 the least amount of labor and operating time; and fourth, to provide other certain improvements in construction as will be hereinafter described.

With these objects in view, my invention 45 consists of a certain novel construction and operating arrangement as will hereinafter more fully be described and pointed out in the claims, reference being had to the accompanying drawing forming part thereof, and in which:

Figure 1, is a view showing the general arrangement of the scraper; Figure 2, a view showing more in detail the method of hinging the transverse plate; Figures 3, 4 and 5,

are views showing the operative action of the scraper; Figure 6, a plan view showing the method of operation in starting to load out a chamber where the working face is full; Figure 7, an elevation of Figure 6; Figure 8, a plan view showing the method of operating with a partially cleared face; Figure 9, an elevation of Figure 8; and Figures 10 and 11, a plan and elevation showing a convenient embodiment of the scraper and mechanism as applied to mining operation.

Similar numerals of reference refer to similar parts throughout the several views, and in which the numeral 1 in Figure 1, designates substantially vertical side plates, the relative position being parallel. The numeral 2, designates a transverse member in rigid relation with the two side plates and disposed at the front end of said side plates. The numeral 3, designates a bracing member rigidly fastened to the back inside end of the said plates and disposed diagonally forward and attached to the member 2 in rigid relation.

This construction allows the back end of the scraper to be open, which is important, as it will allow large lumps of material to be conveniently entrapped between the side plates. Should a transverse back brace be used, it would seriously obstruct the movement of the scraper into the pile and would tend to push the material backward until the motive power would stall without attempting to fill the scraper. It is obvious that other bracing members could be used other than as shown, to accomplish this object, for instance bracing members on the bottom could be used or the diagonal members could be placed outside instead of inside, but the constructions shown is a convenient one to express the object.

The numeral 4 designates a transverse plate disposed between the side plates 1 at the bottom and at the rearward end thereof, and is hinged thereto by means of the threaded stud 5 passing thru an aperture in the plate 4 and held in place by means of the nut 6 thereon. This plate 4 serves as a scoop which is arranged to cut into and under the material on the working stroke of the scraper.

The numeral 7 designates a rope attaching means for the plate 4 and consists substantially of an angle riveted to the back end of

the plate to which the rope 8 is fastened, passing over the front transverse member and thru a guide 9 thereon and joining other ropes hereinafter mentioned. Said angle is 5 provided with a plurality of holes 14, by which the position of the pulling rope attached thereto can be adjusted to cause the plate to dig to a certain amount. The back 10 face of said plate 4 is tapered and the edge scarfed, to give it a cutting and shearing action when sliding into a pile of material.

The numeral 10 designates a stop secured to the rope 8 and adapted to engage with the 15 guide 9 to limit the downward travel of the plate 4, the upward travel being limited by the plate 4 engaging with the diagonal supports 3.

The numerals 11 and 12 designate operating 20 ropes secured to the front bracing member and terminating with the rope 8 into a common ring 13.

The construction of the side plates 1, is such that the front end is turned outward and backward forming an incomplete cylinder, thereby eliminating a sharp edge, while 25 the back end is tapered backward and downward to give it a digging action and helping the scraper to stay on the bottom.

The numeral 15 designates a channel running 30 in a longitudinal direction along the outside of the plate 1, and the numeral 16 designates rollers attached to the said channel, so that there is formed an anti-friction bearing between the scraper plates and any 35 adjacent obstruction.

The numeral 17 designates a runner positioned 40 on the outside and at the bottom of plate 1. This runner protects the nut 6 from mechanical injury and serves also to reduce side friction when the scraper is operating against a side wall.

Having described the various parts of the 45 scraper, its action will be shown in Figures 3, 4 and 5, in which the numeral 18 designates a pile of material to be moved. The numeral 19 designates a tail rope attached to the angle 7 on the transverse plate 4, said 50 rope leading backward around a fixed pulley and thence to the required motive power.

The numeral 20 designates a head rope 55 attached to the ring 13 and thence to the aforesaid required motive power, which is substantially a double drum winch, which is so arranged that one drum is free while the other is in operation and vice-versa. Pull on the rope 19 will pull the transverse plate down close to the floor and carry the scraper backward into the pile of material, as shown in Figure 4. This end being 60 open will therefore not meet with resistance, and large lumps of material can be enclosed between the side plates. It is understood that the ropes 8, 11, 12 and 20 are slack. Pull on the rope 20 will first exert effort on 65 rope 8, raising the transverse plate to its

uppermost position and when this is reached, the ropes 11 and 12 will have become taut and the forward movement of the scraper will be exerted mainly by these ropes. It is understood that the rope 19 is 70 now slack. The resistance of the transverse plate 4 entering the coal is greatly reduced by the reason of the tapered and scarfed cutting edge heretofore mentioned. To meet these conditions, I use a method as shown in 75 Figures 6 to 9 inclusive, in which a working chamber is shown. The numeral 21 designates the working face from which a pile of coal has been blasted down and which covers the floor area across the path of the 80 face.

In an operating system for such a scraper, it is highly important that the operating ropes be kept from under the coal, otherwise considerable power will be lost in friction, and that some method of pulley anchorage at the face must be provided, otherwise time will be lost in digging a path thru the coal to the face in order to set up props behind the coal when the face is full, as 90 directly after the coal has been shot down, and also it is desirable that the scraper be kept in operation avoiding time lost in resetting pulley anchorage.

The numeral 22 designates a pole prop, 95 on one end is fastened the pulley 23 thru which the tail rope 19 is placed and the prop then thrown on top of the coal in a corner. The numeral 24 designates a prop to which the other end of the said pole prop is attached in pivot relation and adapted to position this end of the pole as close to the roof as possible. Said pole prop 22 is of sufficient length to allow the setting of the supporting prop 24 in as clear a floor 105 space as practical.

The numeral 25 designates a pulley positioned 110 at the opposite side of the room and secured to the roof by means of a supporting prop 26. Said tail rope 10 passes around this pulley and thence to the motive power together with rope 20.

By this means the ropes are free of the coal and a pulley supporting means is provided at the face.

The scraper is then operated, cutting a path along the side rib up to the face as close as possible, as which time the pole prop 22 is discarded or set up in an adjacent room and the method shown in Figure 8 is 115 120 then followed which consists substantially of a pulley 27, to which is attached a plurality of chains or ropes of substantially equal length, and at the end of each, there is secured a prop.

It is obvious that the method shown in Figure 6 will clear the coal to the face or so near thereto that little shoveling will be required, and the prop 28 will be set so that the pulley 27 is adjacent to the edge of 125 130

the coal when the scraper is pulled backward into the coal and loaded out as herein-after described.

While this operation is taking place the prop 29 carrying the chain 30 is being set up, and when it is desired to shift the block 27 to a new position the prop 28 is taken down, at which time the block 27 will pull over to its new position by reason of the strain being taken on chain 30.

The prop 28 is then set up and the cycle of operation repeated until the amount of coal blown down is loaded out.

It is intended that the scraper slice off its load from the side of the pile, altho it may be necessary and to an advantage to enter the coal with the total width of the scraper.

It is obvious from the foregoing that the operating ropes are free of the coal, the necessity of setting up props behind the coal in a full face is eliminated, and that no manual work is required except for setting up the props 28 in sequence across the face as that part is loaded out.

In Figures 9 and 10, there is disclosed a convenient embodiment of my said invention, and in which the numeral 35 designates a mine car in the entry into which it is desired to transfer the coal from the working face of the chamber.

The numeral 36 designates a double drum winch set in a room adjacent the entry, to which the operating ropes 19 and 20 are attached. The rope 19 is led to the winch 36 thru suitable pulleys 37 and 38 and the rope 20 is led thereto thru the pulley 39. The numeral 40 designates props, the lower edge on which is secured suitable plank 41 acting as a guide or runway for the scraper.

The numeral 42 designates a portable apron or chute reaching from the car to the entrance of the chamber. When the chamber has been loaded out, the said apron is thrown back out of the way in order to clear the movement of the cars in the main entry.

When the scraper has obtained its load as heretofore described, the head rope 20 pulls the scraper ahead and over said apron 42 allowing the coal to drop into the car.

It is obvious that in case the said runway is long and the scraper is operated other than thru a central path, that the scraper sides will press hard against the runway plank 41. This condition is however relieved by the use of the rollers and the runner 17 placed outside of the plate 1.

It will be understood that in a mining operation several chambers adjacent to each other are being worked and that by means of suitable pulleys the operating ropes can be transferred from chamber to chamber as each is worked out. I am aware that other forms of scrapers have been used, but do not know of any that will accomplish the objects as disclosed in this specification.

I do not wish to limit myself to the exact construction or operation as shown, as it is evident that certain departures can be made therefrom without departing from the spirit and intent of my said invention, but what I claim as new, and desire to secure by Letters Patent, is:

1. A scraper bucket for mine use comprising side plates, bracing means therefore, a scoop member pivoted between said side plates adjacent the material receiving end, means on each side plate functioning under a filling movement of said scraper to cause the material engaging ends of said plates to have a downward digging action, and means for moving said scraper towards and away from the material, said moving means being arranged to hold said scoop substantially horizontal under filling direction movement and to hold said scoop substantially inclined to form a closure for the scraper end under movement in another direction.

2. A scraper bucket comprising side plates, bracing means therefore, a scoop member pivoted between said side plates adjacent the material receiving end, a cutting edge formed on said scoop, means on each side plate functioning under a filling movement of said scraper to cause the material engaging ends to have a downward digging action, and means for moving said scraper towards and away from the material, said moving means being arranged to hold said scoop substantially horizontal under filling direction movement and to hold said scoop inclined to form a closure for the scraper end.

3. A scraper bucket comprising side plates, a scoop member pivoted between said side plates adjacent the material receiving end, means on each side plate functioning under a filling movement of said scraper to cause the material engaging ends of said plates to have a downward digging action, means for moving said scraper towards and away from the material, said moving means being arranged to hold said scoop substantially horizontal under filling direction movement and to hold said scoop inclined or vertical under movement in another direction to form a closure for the scraper end.

4. A scraper bucket for mine use, comprising two oppositely arranged side plates each having its rear edge tapered outwardly and downwardly substantially in the form of a V, a rigid cross-bar connecting the forward ends of said plates, bracing bars extending from substantially the middle portion of said cross-bar and diverging rearwardly and connecting respectively with said side plates to brace said side plates and transmit end

thrusts away from said side plates to said cross-bar, a rear plate pivoted between said side plates and having a rear scarfed edge tapering outwardly from the rear edges of said side plates, said plate being arranged to assume a horizontal position during a loading operation of said scoop and to assume an upright position seating against the said brace bars in filled position of said 10 scraper, and means for simultaneously con-

trolling said scraper plate for moving said bucket rearwardly and forwardly.

In testimony whereof, I have signed my name to this specification in the presence of two subscribing witnesses.

DAVID R. KNAPP.
